(57) **CLAIM**

The ornamental design for a taco shell plate, as shown and described.

DESCRIPTION

FIG. 1 is a top plan view of a taco shell plate of the present invention;

FIG. 2 is a side elevation view of the plate of FIG. 1;
FIG. 3 is a bottom plan view of the plate of FIG. 1; and,
FIG. 4 is a perspective view of the plate.

A stackable plate made of paper or the like for holding one or more edible taco shells and ingredients placed in the taco shells.
